UNITED STATES PATENT OFFICE.

JOSEPH J. DOBES AND BEN JELINEK, OF CHICAGO, ILLINOIS, ASSIGNORS TO THE ANDERSON COMPANY, A CORPORATION OF INDIANA.

TIMER.

Application filed June 21, 1920. Serial No. 390,305.

To all whom it may concern:

Be it known that we, JOSEPH J. DOBES and BEN JELINEK, citizens of the United States, and residents of the city of Chicago, in the county of Cook and State of Illinois, have invented certain new and useful Improvements in a Timer; and we do hereby declare that the following is a full, clear, and exact description of the same, reference being had to the accompanying drawings, and to the numerals of reference marked thereon, which form a part of this specification.

This invention relates to an improved form of timer to be used particularly with Ford automobiles, but which, obviously, can be adapted to any machine and those having any number of cylinders.

The parts of the ordinary commutator, such as the roller, spring, the fibre lining and the metal contacts in the shell, become badly worn in a short time, necessitating frequent replacement in order to obtain efficient operation of the engine. These parts are expensive and can ordinarily be replaced only by a skilled mechanic and at considerable trouble and consequent expense.

In operation, the ordinary commutator becomes clogged with dirt and oil which lodge on the roller, spring, and the fixed metal contacts, likewise in cold weather the oil gums, consequently preventing the proper completion and breaking of the primary current at the correct time, thereby causing the secondary high voltage current to jump the spark gaps in the cylinders at the wrong moment, and sometimes results in the production of such a weak secondary current that no spark will occur at the terminals of the spark plug, thereby causing inefficient operation of the engine.

This invention has for its object the production of a timer which always insures the proper distribution of the current.

A further object of the invention is to provide a commutator which is made of hardened material not likely to wear and which, even if it does wear, will operate in just as efficient a manner as when new.

Another object of the invention is to provide a commutator which will operate positively even if quite a substantial amount of grease and dirt have found their way into the same.

Still another object of the invention is to

provide a timer in which the wiping contacts are self-cleaning.

A still further object of the invention is to provide a commutator made of stock parts, which parts can be assembled without any nicety of adjustment and which will nevertheless result in a perfect timing of the spark in operation.

Other and further important objects of this invention will be apparent from the disclosures in the specification and the accompanying drawings.

The invention (in a preferred form) is illustrated in the accompanying drawings and hereinafter more fully described.

On the drawings:

Figure 1 is an elevation of my improved timer, parts being shown in section.

Figure 2 is a section taken on the line 2—2 of Figure 1, looking in the direction indicated by the arrows.

Figure 3 is a section taken on the line 3—3 of Figure 1, parts being omitted.

Figure 4 is an underside view of the moving contact member.

Figure 5 is a section taken on the line 5—5 of Figure 1, looking in the direction indicated by the arrows.

Figure 6 is a fragmentary side view of one of the fixed contact members, showing the projecting point for retaining same in position.

Figures 7 and 8 represent two different modifications of the contact members, Figure 7 being partly in section.

As shown on the drawings:

The reference numerals 1, 2, 4 and 3 indicate the contact plugs for the lead wires leading from the primary coil of the ignition system of the car and are numbered to correspond with the order of firing of the respective cylinders of the engine. These plugs consist of the ordinary nuts and bolts 11, as shown, and are carefully insulated from the case 10 of the timer by insulating washers 12 and plates 14 of fibre or the like. The plates 14 preferably have at least two parallel sides, and one of these sides is held against the inwardly projecting angular portion of the case 10, as shown in Figure 2, thereby preventing any relative turning of the plate 14. These plates 14 are formed in the shape of circular arcs so as to fit closely against the inner sides of the case 10 and their turning about the bolts 11 is there-

2
by further prevented. The plugs 1, 2, 4 and 3 also hold in fixed position the extending contact members 16, which are preferably made of steel or other wear-resisting metal. These plates 16 are provided with points 18, which project into the fibre plates 14 when the bolts of the plugs are tightened, whereby any relative turning of the contact plates 16 is positively prevented.

10 Removably mounted on the projecting end of the cam shaft 19 is the moving contact member 20, which replaces the ordinary roller and roller arm. The contact member 20, is pivoted at 22 to a cap 24, which fits on the end of the cam shaft 19 and is held fixed thereon by means of a nut 26, cap washer 28 and key pin 30. The contact member 20 is normally held in operative position by a helical spring 32, as shown, and a lever 35 is provided for connection with the spark adjusting control.

In the modification shown in Figure 7, the extending fixed contact member 16^a is not curved but is made as an integral extension of the bolt 11, constituting a bolt 11^a with a round or square head 16^a and is held in position by the nut 1 and insulating washers 12 and 14^a, the washer 14^a being made thicker in this case. This contact 16^a is held in position without the necessity of the points 18.

Figure 8 represents another modification in which the fixed contact member 16^b is bent backwardly in the form of a U and is held in position by means of small projections or points 18 in the same manner as those of the S-shaped blade 16, the points (not shown) co-operating with the fixed insulating washer 14 as in the case described.

The operation is as follows:

The cap 24 having the contact member 20 pivotally mounted thereon is placed on the end of the cam shaft and the key pin 30 inserted to hold the same in fixed position against slipping around the shaft. The cap washer 28 and nut are then fixed in place thereby holding the pin 30, the cap 24, and the contact member 20 in fixed position on the end of the cam shaft 19. The fixed contact members 16 are assembled in the case 10 in an obvious manner by means of the bolts 11, the straight side of the fibre insulating washer 14 and the points 18 acting to hold the members 16 in positively fixed position. As these members 16 are all stampings and therefore all exactly alike, and as the bolts 11, fibre washers 12, and the plates 14 are also all exactly alike, respectively, the contact members 16 can be quickly and easily placed in their correct positions in the case 10 without any possibility of error, and the resultant perfect spacing insures a correct timing of the spark.

The spring 32 acts to produce positive contact at every point with equal pressure on each, and this spring pressed wiping action also acts to keep the points clean, and the offset of the contacting ends of the members 16 from the walls of the casing will insure positive operation of the timer at all times even when it is partly filled with grease and dirt. Further, the members 16 are so spaced from each other that the movable contact member 20 cannot make contact with more than one at a time, thereby positively avoiding short circuits.

As shown, the cam shaft 19 and the contact member 20 rotate in a clockwise direction, thereby producing sparks in the cylinders 1, 2, 4 and 3 successively, and an extending lug 34 is provided on the member 20 to prevent the spring 32 from pushing it into an abnormal position while it is between two members 16, thereby preventing any possibility of contact with two members 16 at once. It will be seen that the break between the members 16 and 20 is sharp, thereby producing the desired hot spark. The projecting lever 35 is provided in order to allow of the advancing or retarding of the spark in the ordinary manner.

While specific embodiments of the invention are illustrated in the drawings, it will of course be understood that minor changes and obvious variations may be made in the particular constructions shown, and the invention may be embodied in other forms, as will appeal to those skilled in the art and falling within the scope of the appended claims, without departing from the spirit of the invention.

We claim as our invention:

1. A timer including a casing, a plurality of contact members on the casing, a rotary shaft disposed centrally of the casing, and having a contact member to cooperate with the first mentioned contact members on the casing, the contact member of the rotary shaft comprising a rigid metal plate pivotally connected at one end to said shaft, resilient means for pressing the outer part of said pivotal contact member outwardly, each of the contact members on the casing consisting of a continuous substantially rigid metal strip shaped to provide a base portion at one end thereof secured to the casing, an intermediate outstanding part at one end of said base portion, and an outer contact portion spaced from the casing and extending at an angle to said outstanding part and forwardly therefrom to one side of said base portion, whereby a firm support for the contact portion is afforded while providing for slight yielding thereof to prevent rebounding upon impact of the rotary contact member therewith.

2. A timer including a casing, a plurality

- of contact members on the casing, and a rotatable contact member to cooperate with the first mentioned contact members on the casing, the contact member of the rotary 5 shaft comprising a rigid metal plate pivotally connected at one end to said shaft, and resilient means for pressing the outer part of said pivoted contact member outwardly, each of the contact members on the casing 10 consisting of a continuous substantially rigid metal blade of substantially S-shape form to provide a base portion at one end thereof secured to said casing, an intermediate outstanding part, and an outer contact portion, whereby a firm support for the outer contact portion is afforded while providing for slight yielding thereof to prevent rebounding upon impact of the rotary contact member therewith. 15 3. A timer including a casing, a plurality of substantially rigid metal contacts on the casing having contact portions spaced from the wall of the casing, in combination with a rotary shaft disposed centrally of the casing 20 and having a contact member to cooperate with the first mentioned contact members on the casing, the contact member on the rotary shaft comprising a continuous rigid metal plate pivotally connected at one end 25 to said shaft, said plate having an outer curved contact portion and reinforcing side web portions for said curved contact portion extending along the sides thereof, and resilient means for pressing the outer curved 30 contact part of the last mentioned contact member outwardly. 35 4. A timer for internal combustion engines, comprising, in combination, a casing, a plurality of fixed contact members in said casing, each of said contacts being a substantially S-shaped blade, one of the limbs of said blade being curved to conform to the circular wall of the casing, and having a hole therethrough, a bolt in said hole for 40 securing the contact member to the inner surface of said casing, there being two insulating washers upon each bolt, one outside and one inside the casing, the inside washers being fixed against rotation, projections on the fixed contact members, said 45 projections being embedded in the fixed 50 washers, a shaft in said casing and projecting therefrom to connect with the engine, a rotor removably secured to said shaft, said rotor having an extension, a movable contact member or brush pivoted to said extension, said brush being a hollow curved stamping the convex side of which is in the direction of the S-shaped contact members. 55 6. A timer including a casing, a plurality of contacts on the casing, a rotatable contact member to cooperate with the first mentioned contacts on the casing, each of the contact members on the casing comprising a continuous substantially rigid metal strip having a base portion at one end thereof secured to the casing, an intermediate outstanding part, and an outer contact portion extending at an angle to said outstanding 60 part in a plane spaced from said base portion, whereby a firm support for the contact portion is afforded while providing for slight yielding thereof to prevent rebounding upon impact of the rotary contact member therewith. 65 7. A timer including a casing, a plurality of contact members on the casing, a rotatable contact member to cooperate with the first mentioned contacts on the casing, each of the contact members on the casing comprising a continuous substantially rigid metal strip having a base portion at one end thereof secured to the casing, an intermediate outstanding part, and an outer contact portion extending at an angle to said outstanding part and forwardly 70 therefrom to one side of said base portion, whereby a firm support for the contact portion is afforded while providing for slight yielding thereof to prevent rebounding upon impact of the rotary contact member therewith. 75 8. A timer including a casing, a plurality of contact members on the casing, a rotatable contact member to cooperate with the first mentioned contacts on the casing, each of the contact members on the casing comprising a continuous substantially rigid metal strip having a base portion at one end thereof secured to the casing, an intermediate outstanding part, and an outer contact portion spaced from the casing and extending at an angle to said outstanding part and forwardly 80 therefrom to one side of said base portion, whereby a firm support for the contact portion is afforded while providing for slight yielding thereof to prevent rebounding upon impact of the rotary contact member therewith. 85 9. A timer including a casing, a plurality of contact members on the casing, a rotatable contact member to cooperate with the first mentioned contacts on the casing, each of the contact members on the casing comprising a continuous substantially rigid metal strip having a base portion at one end thereof secured to the casing, an intermediate outstanding part, and an outer contact portion spaced from the casing and extending at an angle to said outstanding part and forwardly 90 therefrom to one side of said base portion, whereby a firm support for the contact portion is afforded while providing for slight yielding thereof to prevent rebounding upon impact of the rotary contact member therewith. 95

In testimony whereof, we have hereunto subscribed our names in the presence of two subscribing witnesses.
